CARTRIDGE CLIP FOR FIREARMS

John C. Garand, Springfield, Mass., assignor to
the Government of the United States of
America, as represented by the Secretary of
War

Application May 22, 1929, Serial No. 365,205
4 Claims. (Cl. 42—88)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a cartridge clip for holding ammunition in fire arms.

In devising a clip for ammunition it is desirable that it be of light construction but at the same time durable; that it be so formed as to hold the 10 ammunition properly staggered or nested; that it hold the ammunition firmly yet allow of its easy insertion and withdrawal; that it permit the ammunition to be evenly and properly fed; that it be capable of insertion into the fire arm either end 15 first and that it be firmly held in the fire arm.

These desired objects are attained in the present instance by the provision of a clip suitably curved to properly stack the ammunition and lend strength to the clip; by providing a reduced area contact between the sides of the clip and the ammunition through ribs, corrugations or the like, which also serve to further strengthen the structure and allow the use of light material; by constructing the clip of such dimensions that ammunition may be stacked therein only in the proper position to be evenly fed therefrom and by making a symmetrical clip formed with suitable elements to cooperate with the retaining element of the fire arm.

With these and such other objects in view as 30 may hereinafter more fully appear, the invention resides in the novel arrangement and combination of parts and in the details of construction hereinafter described and claimed it being understood, however, that changes in the precise embodiment 35 of the invention herein disclosed may be made within the scope of what is claimed without departing from the spirit of the invention.

A preferred embodiment of the invention is 40 shown by way of illustration in the accompanying drawing wherein:

Fig. 1 is a view in front elevation;

Fig. 2 is a view in side elevation;

Fig. 3 is a central transverse section;

Fig. 4 is an enlarged view in front elevation 45 illustrating the positions assumed by the cartridges when an even number are in the clip;

Fig. 5 is the same view illustrating the positions assumed by the cartridges when an odd number are in the clip; and

Fig. 6 is a plan view.

Referring to the drawing by numerals of reference:

The clip consists of a backplate 1 curved to 55 properly stack the ammunition and incidentally

to lend strength to the structure. The backplate is formed at each end with cut away portions or apertures 2 to permit ammunition to be properly fed from the clip. Extending from the backplate are the side plates 3 which converge toward the 5 front to firmly contact and retain the ammunition. At the juncture of the side plates with the backplate they are offset inwardly to form guide elements 4 which extend longitudinally of the clip and preferably merge into the side plates 10 adjacent to the ends thereof. These elements serve to guide or position the clip within the fire arm and are preferably rectangular in cross section and so proportioned that binding of the clip during insertion is prevented even though the inserting pressure be applied considerably to one 15 side of the plane of the ribs. Means are provided for cooperating with a retaining element of a fire arm for holding the clip in place therein such means preferably consisting in a notch 5 formed in each rib the notches so located that cooperation with the retaining element will be had whichever end of the clip be inserted initially into the fire arm.

Each of the side plates 3 has on the inner side 20 thereof and adjacent to the backplate a longitudinal rib 6 which serves the purpose of contacting the ammunition and reducing surface friction thereby rendering sliding of the ammunition within the clip easier and also of anchoring the cartridges within the clip with the exception 25 of the two end cartridges. At or near its outer edge each side plate has a similarly extending rib 7 which also serves the purpose of contacting the sides of the cartridges to reduce surface friction. These ribs 6 and 7 serve the further purpose of 30 strengthening the side plate.

The ends of each rib 7 are curved inwardly to 35 form the respective edges or projections 8 or 8' from whence the ribs merge into the curved ends 9 or 9' of the side walls, thus forming, with the edge 8 or 8', the edge 10 or 11 of the side wall, and the surface of the next succeeding cartridge, a suspension for the piece of ammunition next to be fed from the clip which renders feeding of the 40 ammunition exceedingly easy. These edges or projections 8 and 8' also serve the purpose of preventing angular movement of the cartridges within the clip which angular movement may occur with cartridges which have not yet arrived 45 at feeding position, or with cartridges which have arrived at such position due to the sudden blow of the bolt on the head thereof in which case the angular movement of the cartridge is in the reverse direction.

It will be noted that the curved end 8 of each side wall terminates short of the curved end 10 a construction which renders it impossible to load the clip except in a manner which assures proper feeding of the ammunition from the clip.

I claim:

1. An ammunition clip for holding two rows of cartridges in staggered relation and adapted to be inserted into the magazine of a firearm embodying a back plate, side plates extending from the back plate, inwardly curved ends on the side plates, and projections on the side plates adjacent to the ends extending into the rectilinear paths of travel of the cartridges as they are elevated through the clip.

2. An ammunition clip for holding two rows of cartridges in staggered relation and adapted to be inserted into the magazine of a firearm embodying a back plate, side plates extending from the back plate, inwardly curved ends on the side plates, and inwardly extending projections at

the junctures of the forward edges of the side plates and curved ends.

3. An ammunition clip for holding two rows of cartridges in staggered relation and adapted to be inserted into the magazine of a firearm embodying a back plate, side plates extending from the back plate, inwardly curved ends on the side plates the curvature of the ends struck on a radius less than the radius of the cartridge case, and inwardly extending projections at the junctures of the forward edges of the side plates and curved ends.

4. An ammunition clip for holding two rows of cartridges in staggered relation embodying a back plate, side plates extending from the back plate, and ribs, formed at the junction of the side plates with the back plate, extending outwardly beyond the planes of the side plates to position and guide the clip when inserting the same into a firearm and permit stacking of rim or rimless cartridges into the clip.

JOHN C. GARAND.
